ATTACHMENT FOR SAFE KNOBS

Harry W. Srygley, Abilene, Tex.

Application May 31, 1933, Serial No. 673,664

14 Claims. (Cl. 109—6)

My invention relates to the class of devices designed to be applied to a safe, and especially to the combination dial or knob thereof, which comprise a frangible container of noxious gas, serving to protect the combination against attack and damage.

The object of my invention is to provide a protective covering attachment of this class which is self-contained, requiring no alteration or adaptation of the safe and its fittings, which may be attached readily to the combination dial, and when so attached will resist all unauthorized attempts to remove the attachment, or injure the combination without breaking the container of noxious gas; and to that end my invention resides in the novel construction and arrangement of parts hereinafter described and particularly pointed out in the claims.

Referring now to the drawing, in which like characters represent like parts:

Fig. 1 is a vertical elevation of my device in position on the safe door, the knob, 16, being shown in dotted lines, this elevation being partly in section along the lines, 1—1 of Fig. 2;

Fig. 2 is a side view, in vertical section, of the safe door and combination dial with my device attached thereto; and

Fig. 3 is a sectional view of the collar, 17, taken on the line, 3—3 of Fig. 1.

In the safe door, 11, there is the usual annular ridge, 12, on which the zero mark is placed, and within same the usual rotatable combination dial piece, 13, having the number marks, 14, on the outer circular edge of the front surface, and the knob, 16, having an intermediate narrowed portion, 15, as is usual in safes of ordinary manufacture.

Surrounding and securely fastened to the knob, 16, so as to turn therewith is the collar, 17, of my device. This collar has inner and outer cylindrical surfaces, the bottom or inward end, 18, which rests against the surface of the dial being rounded or beveled, in order that it may more readily fit snugly against any dial piece, since the front surfaces of dial pieces of different manufacture vary in contour. The top or front end of the collar, 17, has an outwardly extending flange, 19.

Extending inwardly through tapped holes in the cylindrical portion of the collar, 17, are four set screws, 21, disposed ninety degrees apart, the axis of each being set at an angle with the bottom of the collar, which I find should be from eleven to fifteen degrees, the inner ends thereby being higher. These set screws are screwed in-

wardly until they bear against the narrowed portion, 15, of the knob, 16; centering the collar, 17, about the axis of the dial piece, 13, at the proper setting, or angular position, as hereinafter shown. The thrust of the set screws, 21, so adjusted, serves to press the bottom, 18, of the collar, 17, firmly against the front surface of the dial piece, 13, so that the collar, 17, and the rest of my device attached thereto, will rotate with the dial piece, 13, upon the same axis. The set screws, 21, when covered by the rest of the device, as hereinafter shown, are inaccessible from without and can not be loosened.

To provide for knobs of different shape I place a second series of tapped holes, 22, nearer the base, 18, of the collar, 17, in which the set screws, 21, may be placed when mounting my device on dial pieces having such knobs.

Into the annular portion of the collar, 17, I drill three holes from the top of the collar, 75 spaced a slightly unequal number of degrees apart. In each of these holes is placed a dowel pin, 23, each pressed by the spring, 24, upwardly beyond the top surface of the collar, 17. These pins, 23, have one end rounded, and the other end tapering to a point, and obviously may be reversed at choice so that either end may be chosen for the top.

At equal angular distances in the same direction of rotation from the dowel pins, 23, I tap 85 holes through the flange, 19, to receive the cap screws, 25, which have a short shoulder, 26, next to the slotted head, 27, but smaller in diameter. As may be required for spacing, I place shim washers, 28, of larger outside diameter, under 90 the shoulder, 26.

On the collar, 17, rests the disk portion, 29, of the drum, 31, being in front of the front or top surface of the collar, 17, and having substantially the same inside diameter as the collar, 17, the outer diameter being slightly greater, so that the drum, 31, may cover the flange, 19, the conical portion thereof flaring away from the collar, 17, and extending back toward the safe.

In the disk portion, 29, are disposed holes, 32, corresponding to the dowel pins, 23, but of lesser diameter. At equal angular distances from holes, 32, are the beginnings of slots, 33, of such width, radially, that they will slide over the shoulders, 26, of cap screws, 25. These slots, 33, being of equal length along the arc, terminate in circular openings, 34, large enough to fit over the heads, 27, of cap screws, 25, at the same time, when by turning the drum, 31, the slots, 110

33, ride on the shoulders, 26, until the end of the slot, 33, is reached, at which point the dowel pins, 23, will click into the holes, 32. It will be noticed that the length of the shoulder, 26, is slightly greater than the thickness of the flat or disk portion, 29; and that the spacing shim washers, 28, serve to separate the disk portion, 29, from the collar, 17.

When the rounded ends of dowel pins, 23, are turned out, the drum, 31, will be held in position when they click, but may be turned when pressure is applied, the pins sliding enough to release the drum; but when the pointed ends of the pins are turned out, they serve to hold the drum firmly against all pressure that can be applied.

The outer surface of the conical portion of the drum, 31, is roughened by outwardly pressed punch marks, or eruptions, 35, scattered over the surface. This is done to promote adhesion of the layer, 36, of plaster of Paris, or other suitable cement by which the drum, 31, is attached to the adjacent zone or portion of the concave surface of the back part, 37, of the glass container.

The glass container consists of two substantially hemispherical glass shells, the inner shell, 37, being welded to the outer shell, 38, at the back edge, 39, where they join, leaving between them a meniscus shaped chamber, 41, which is filled with noxious gas in liquid form, 42, through a sealable glass nipple, 43, located at the pole of the outer shell, 38.

The glass container overlies the knob, 16, collar, 17, and drum, 31, extending back nearly to the surface of the safe door, 11, its convex side being towards the front. The exterior surface of the glass in the lower zones is roughened by welding thereto small bits of glass to form eruptions, 44, which likewise promote adhesion of the cement. The second layer of cement, 45, serves to attach the metallic bowl to the outer shell, 38, of the glass container.

The metallic bowl consists of a front short cylindrical portion, 46, for the base of the bowl, an intermediate flaring portion, 47, and an outwardly flaring rim, 48. The inner surface of the flaring bowl portion, 47, is roughened by welding thereto small bits of metal, 49, to promote adhesion of the cement layer, 45.

The metallic bowl, glass container and drum, 31, constitute the cover of my device, as distinguished from the collar, 17, to which they may be attached and locked as shown. The rim, 48, when the cover is attached, extends as close to the safe door surface, 11, as is practicable for operation, leaving some slight clearance, the amount of which may be adjusted by varying the shim washers, 28.

Since the cover, and especially the rim, 48, when attached, covers the dial number marks, 14, and the annular ridge, 12, bearing the zero mark, the rim, 48, is graduated with number marks, 51, corresponding to the number marks, 14, and a new zero mark, 52, corresponding to the old zero mark, is marked on the safe door surface, 11, above the rim, 48. In order to readily adjust my device in correspondence with the number marks, 14, I place a mark or marks on the collar, 17, indicating the angular position corresponding to the hundred mark of the marks, 51, on the rim, 48. Such a mark is shown at 53 as a groove on the inner surface of the collar, 17.

In the construction of my device I first attach

the gas filled glass container to the flaring bowl portion, 47, by means of the cement layer, 45; next I attach the drum, 31, to the inside of the glass container by means of the cement layer, 36, taking care to line the drum up with the rim, 48. I then insert the collar, 17, turning it to where the dowel pins, 23, click, having their rounded ends outward, and mark on it a hundred mark such as the groove, 53.

In applying my device to a safe I first adjust the collar, 17, firmly on the safe dial piece, 13, using the mark, 53, to get the angular setting; then I put on the cover, letting the dowel pins, 23, click with their rounded ends; I then check the angular setting of markings, 51, with markings, 14, and try operating the combination with markings, 51, and if, necessary, remove the cover and readjust the collar.

To remove the cover from the collar, 17, at this time, it will be necessary to hold the dial piece, 13, against rotation, which can be done with all safes of which I have knowledge, especially when the door is open.

I further in like manner adjust the thickness of the shim washers, 28, to secure proper clearance of the dial knob, 16, to provide uniform clearance between the bowl rim, 48, and safe door surface, 11, and to let the attachment spin properly. When the adjustments are completed the dial piece, 13, with my attachment fastened thereto and covering same, can be rotated as a whole, and the combination operated without difficulty.

For safes that have no way of holding the dial piece, 13, against turning when the safe is closed the rounded ends of dowel pins, 23, may be used permanently, as it will be impossible to remove the cover after they have clicked unless the dial piece can be held. On such safes my device may be taken off whenever the safe door is open so that the dial piece can be held.

On other safes it will be necessary to use the sharp ends of dowel pins, 23, when mounting the cover as a safeguard, and once so locked home it can not be removed without breaking. When the glass container is broken the metal bowl may be removed by force, giving access to the drum disk, 29, so that the dowel pins, 23, may be released. Whenever such breakage occurs a new cover may be put on the collar, making adjustments as above described.

What I claim as new, and desire to secure by Letters Patent of the United States of America, is:

1. A protective covering for safe combination dial pieces, attached thereto and rotatable therewith, the attaching means being within the cover, and having a frangible container of noxious gas disposed within the cover and attached thereto and conforming to the inner surface thereof.

2. A protective covering for safe combination dial pieces, attached thereto and rotatable therewith, the cover having radial markings for operating the combination, the attaching means being within the cover, and having a frangible container of noxious gas so disposed within the cover as to break under attack.

3. A protective covering for safe combination dial pieces, attached thereto and rotatable therewith, the cover having radial markings for operating the combination, the attaching means being within the cover and inaccessible from without, and having a frangible container of

noxious gas so disposed within the cover as to break under attack.

4. A protective attachment for safe combination dial pieces, having a cover within which there is disposed a frangible container of noxious gas conforming to the inner surface of the cover, a collar, means for attaching the collar firmly to the dial piece, such means being enclosed by the cover and inaccessible from without, and locking means within the cover for locking the cover to the collar.

5. A protective attachment for safe combination dial pieces, having a cover in which there is a frangible container of noxious gas, a collar, means for attaching the collar firmly to the dial piece, such means being enclosed by the cover and inaccessible from without, and locking means within the cover for locking the cover to the collar, the cover rotating with the dial piece and having radial markings for operating the combination.

6. A protective attachment for safe combination dial pieces, having a cover in which there is a frangible container of noxious gas, a collar, means for attaching the collar firmly to the dial piece, and locking means for locking the cover to the collar operated by turning one relatively to the other, both such attaching and locking means being enclosed by the cover and inaccessible from without.

7. A protective attachment for safe combination dial pieces, having a cover in which there is a frangible container of noxious gas, a collar, means for attaching the collar firmly to the dial piece, and locking means for locking the cover to the collar operated by turning one relatively to the other, both such attaching and locking means being enclosed by the cover and inaccessible from without, the cover rotating with the dial piece and having radial markings for operating the combination.

8. A protective attachment for safe combination dial pieces, having a cover in which there is a frangible container of noxious gas, a collar, means for attaching the collar firmly to the dial piece, and locking means for locking the cover to the collar operating automatically upon turning one relatively to the other, both such attaching and locking means being enclosed by the cover and inaccessible from without.

9. A protective attachment for safe combination dial pieces, having a cover in which there is a frangible container of noxious gas, a collar, means for attaching the collar firmly to the dial

55

piece, and locking means for locking the cover to the collar operating automatically upon turning one relatively to the other, both such attaching and locking means being enclosed by the cover and inaccessible from without, the cover rotating with the dial piece and having radial markings for operating the combination.

80

10. In a device of the class described, a collar firmly attached to the dial piece, a cover, engaging means holding the cover to the collar but permitting transverse motion, and locking means to lock against such transverse motion, all such attaching, engaging and locking means being enclosed by the cover and inaccessible from without.

85

11. In a device of the class described, a collar firmly attached to the dial piece, a cover, engaging means holding the cover to the collar but permitting relative rotation, and locking means to lock against such relative rotation, all such attaching, engaging and locking means being enclosed by the cover and inaccessible from without.

90

12. In a device of the class described, a collar firmly attached to the dial piece, a cover, engaging means holding the collar to the cover but permitting relative rotation, and spring pressed pins alining with corresponding depressions for locking the cover to the collar, all such attaching, engaging and locking means being enclosed by the cover and inaccessible from without.

95

13. In a device of the class described, a collar firmly attached to the dial piece, a cover, engaging means holding the cover to the collar consisting of cap screws in one sliding in arced slots in the other, and spring pressed pins alining with corresponding depressions for locking the cover and collar against relative turning, all such attaching, engaging and locking means being enclosed by the cover and inaccessible from without.

100

14. In a device of the class described, a collar firmly attached to the dial piece, a cover, engaging means holding the collar to the cover but permitting relative rotation, and spring pressed pins alining with corresponding depressions for locking the cover to the collar, all such attaching, engaging and locking means being enclosed by the cover and inaccessible from without, the cover rotating with the dial piece and having radial markings for operating the combination.
